UNITED STATES PATENT OFFICE.

OSCAR CARLSON, OF MINNEAPOLIS, MINNESOTA.

COMBINED MOP HEAD AND WRINGER.

Application filed January 23, 1928. Serial No. 248,696.

My invention has for its object to provide a simple and highly efficient mop head and wringer, and to this end it consists of the novel devices and combinations of devices hereinafter described and defined in the claims.

In the accompanying drawings, which illustrate the invention, like characters indicate like parts throughout the several views.

10 Referring to the drawings:

Fig. 1 is a perspective view of the invention with the mop ready for use;

Fig. 2 is a view corresponding to Fig. 1 with the exception that the hand crank has 15 been released and moved into a position to partly wind the mop on the mop-holding roll and wring the same between the two rolls;

Fig. 3 is a view principally in section taken 20 on the line 3—3 of Fig. 2;

Fig. 4 is a view partly in elevation and partly in section taken on the line 4—4 of Fig. 2;

Fig. 5 is a detail view in section taken 25 on the line 5—5 of Fig. 2;

Fig. 6 is a fragmentary detail view principally in section taken on the line 6—6 of Fig. 2, on an enlarged scale;

Fig. 7 is a fragmentary detail view in section taken on the line 7—7 of Fig. 6, with 30 some parts shown in different positions by means of broken lines and with some parts released;

Fig. 8 is an end elevation of the mop-holding roll;

Fig. 9 is a view corresponding to Fig. 2 but showing the manner in which the combined mop head and wringer is held and operated to wind the mop on the mop-holding 40 roll to wring the same or unwind the mop therefrom after the same has been wrung;

Fig. 10 is a view partly in side elevation and partly in section taken on the line 10—10 of Fig. 9 with certain parts shown in part 45 by means of broken lines;

Fig. 11 is a fragmentary detail view with some parts sectioned on the line 11—11 of Fig. 1, on an enlarged scale; and

Fig. 12 is a view partly in elevation and 50 partly in section taken on the irregular line 12—12 of Fig. 11.

The mop head includes upper and lower yoke-like members 12 and 13, respectively, the latter of which is provided with a tubular shank 14 rigidly secured to the transverse

portion of said lower head member at the center thereof. These head members 12 and 13 are slidably mounted the one upon the other by having the transverse portion of the upper head 12 extended through a pair of 60 aligned slots 15 in the shank 14 for sliding movement longitudinally thereof. Said head members 12 and 13 are further slidably connected by making the prongs of the lower head member channel-shaped in cross section and slidably mounting the prongs of the upper head member therein. These channel-shaped prongs of the lower mop member 13 also greatly strengthens the mop head.

A long mop handle 17, only a portion of 70 which is shown, has its lower end portion fitted into the shank 14 and rigidly secured thereto with its lower end axially spaced from the upper head member 12. In addition to the sliding engagement of the transverse portion of the upper head member 12 with the shank 14, said member and shank are further slidably connected and the shank braced from the upper head member 12 by a collar 18 slidably mounted on the shank 14 and a pair of arms 19 that rigidly connect said collar to the outer ends of the transverse portion of the upper head member 12.

A coiled spring 20 is mounted within the tubular shank 14 and is compressed between the upper head member and the lower end of the handle 17 and yieldingly draws the transverse portions of the head members 12 and 13 toward each other. A relatively long 80 flat plate rigidly secured to the upper head member 12 extends into the spring 20 and co-operates with said member to afford a seat 21 for said spring. Carried by the prongs of the upper and lower head members 12 and 13 are upper and lower co-operating wringing 85 rolls 22 and 23, respectively. The lower rolls 23 also afford a holder for a mop *x*, as will presently appear. Said upper roll 22 is provided with headed trunnions 24 which extend through longitudinally extended slots 25 in the prongs of the lower head member 13 and are journaled in the prongs of the upper head member 12.

The roll 23 is tubular and has formed therein a wide longitudinally extended slot 26 which extends completely therethrough. Said lower roll 23 is also provided with end members 27 that are loose from said roll in opposite directions for a considerable distance from the slot 26 whereby said roll may 100 105 110

be flattened to partially close or reduce the width of the slot 26 and radially offset a portion of the roll 23 at one side of said slot from the other, for a purpose that will prevent 5 entirely appear. Extending axially through the lower roll 23 is a tubular mop holder and spacing core 28 that is square in cross section. This core 28 extends through square holes 29 in the end members 27 of the roll 23 and thereby connect said roll and core for common rotation. Said core 28 at its ends engages the opposing faces of the prong of the lower head member 13, which are extended outward of the ends of the prongs of the upper 10 head member 12, and hold the same laterally spaced.

The lower roll 23 is rotated in one direction by a hand crank 30 to wind the mop α thereon and wring the same between the two rolls 22 and 23, and then rotated in a reverse direction to unwind said mop from the roll 23 after the same has been wrung. This hand crank 30 is provided with a long spindle 31 which extends through the core 28 and the prongs of the lower head member 13. Said spindle 31 except at its ends is square in cross section and snugly fits in the core 28 to connect said core and hence the roll 23 to the spindle 31 for common rotation. The ends of the spindle 31 are round and journaled in the prongs of the lower head member 13. The outer ends of the spindle 31 project outward of the respective prong of the lower head member 13 and has applied thereto a washer 32 and a pin 33 which, together with the arm of the hand crank 30, holds said spindle against endwise movement in the prongs of said head member and also hold said prongs against lateral spreading movement.

The hand-piece 34 of the hand crank 30 has a tubular body on the outer end of which is a knob 35. The body member of the hand-piece 34 is mounted in the outer end of the arm of said crank for endwise sliding movement transversely thereof and is held from turning therein by a key-acting spring latch 36 attached to said member and extending into a key way 37 in said arm. An annular shoulder 38 on the inner end of the body of the hand-piece 34 is arranged to engage the inner face of the arm of the hand crank 30 and limit the outward endwise movement of said hand-piece. The latch 36 when the hand-piece 34 is in its outermost position and stopped by the shoulder 38 engages the outer face of the arm of said hand crank and holds the same against inward endwise movement.

When the device is used as a mop, the hand crank 30 is positioned directly over the adjacent prongs of the head members 12 and 13 and the body of the hand-piece 34 moved into the tubular transverse portion of the head member 12 which affords a lock seat 39 therefor. The frictional engagement with the

spring latch 36 and seat 39 releasably hold the body of the hand-piece 34 in said seat.

Formed in the outer end of the arm of the hand crank 30 and the adjacent arm 19 are depressions 40 and 41, respectively, arranged to receive the thumb of the operator's hand, when holding the knob 35, to assist in positioning said hand crank with the body of its hand-piece 34 aligned with the seat 39. When the body of the hand-piece 34 is in its seat 39, the hand crank 30 is held thereby against swinging movement, the head members 12 and 13 are held against sliding movement in respect to each other and the roll 23 is held from turning.

When the device is used as a wringer, the same is held by the operator, as indicated by the hands γ in Fig. 9. Corrugations are formed in the under surface of the transverse portion of the head member 13 to afford finger holes 42. A knob 43 like the knob 35 is secured to the head member 12 at the opposite side from the hand crank 30 to give the device a symmetrical appearance.

The mop α illustrated is of the knitted type and comprises inner and outer plies folded upon themselves. Said mop α is attached to the roll 23 by having the folded portion of its inner ply inserted into the mop-holding roll 23 through the slot 26 and the core 28 inserted through the looped portion of said inner ply. The longitudinal edge portions of the mop-holding roll 23 at the slot 26 are then pressed toward each other to pinch the folded inner ply of the mop α therebetween and it is important to note that said edge portions are radially offset from each other, as best shown in Figs. 3, 7 and 10. The purpose of radially offsetting the longitudinal edge portions of the mop-holding roll 23 is to cause the mop α to wind thereon concentric with said roll to eliminate any ridges or bumps in the mop α that would interfere with the wringing thereof. Outward of the slot 26 the two plies of the mop α are stitched or otherwise fastened together, as indicated at β . The mop α completely covers the roll 23 so that pressure may be applied thereto so as to rub that portion of the mop directly under the roll 23 on the floor.

To wring the mop α the hand-piece 34 is drawn out of its seat 39 and then the hand crank 30 operated to turn the roll 23 and wind the mop α thereon until the free end portion of said mop passes under the roll 23 and drops down. The direction of movement of the hand crank 30 is then reversed and operated to unwind the mop α from the roll 23.

What I claim is:

1. A combined mop holder and wringer having a head comprising upper and lower yoke-like members, the latter of which is slidably mounted within the former, the transverse portions of the yoke-like members

- being closely positioned to afford a hand grip, a mop-holding lower roll journaled to the prongs of said upper member, an upper roll journaled to the prongs of said upper member, said two rolls being movable into co-operating wringing relation by pressing the transverse portions of said members toward each other, and means for rotating the lower roll to wind a mop thereon or unwind on or unwind the same therefrom. 55
5. A combined mop holder and wringer having a head comprising upper and lower yoke-like members, said lower member having a tubular shank on its transverse portion, the transverse portion of said upper member being slidably mounted in a transverse slot in the shank, the prongs of said lower member being channel-shaped in cross section and the prongs of said upper member being slidably mounted therein, a collar slidably mounted on the shank, a pair of arms rigidly connecting the collar to said upper member, a mop-holding lower roll journaled on the prongs of said lower member, an upper roll 60 having trunnions extending through longitudinally extended slots in the prongs of said lower member and journaled on the prongs of said upper member, a coiled spring compressed between an abutment in the shank 65 and said upper member and operative to yieldingly hold the rolls in co-operating wringing relation, and means for rotating the lower roll to wind a mop thereon or unwind the same therefrom. 70
10. the same therefrom.
2. A combined mop holder and wringer having a head comprising upper and lower yoke-like members, the latter of which is slidably mounted within the former, the 15 transverse portions of the yoke-like members being closely positioned to afford a hand grip, a mop-holding lower roll journaled to the prongs of said upper member, an upper roll journaled to the prongs of said upper member, a spring tending to move said lower member in a direction to cause its transverse portion to approach the transverse portion of the upper member and yieldingly hold said rolls for co-operating wringing action, 20 and means for rotating the lower roll to wind a mop thereon or unwind the same therefrom. 25
3. The structure defined in claim 1 in further combination with a shank on the transverse portion of the lower yoke-like member and in which the transverse portion of the upper yoke member has sliding interlocking engagement with the shank. 30
4. The structure defined in claim 1 in which the prongs of the lower yoke-like member are channel-shaped in cross section and in which the prongs of the upper yoke-like member are slidably mounted therein. 35
5. A combined mop holder and wringer 40 having a head comprising upper and lower yoke-like members, said lower member having a tubular shank on its transverse portion, the transverse portion of said upper member being slidably mounted in a transverse slot in the shank, the prongs of said members being slidably mounted, the one upon the other, a mop-holding lower roll journaled to the prongs of said lower member, an upper roll journaled to the prongs 45 of said upper member, a spring compressed between an abutment in the shank and the transverse portion of said upper member and operative to yieldingly hold the rolls in co-operating wringer relation, and means for 50
- rotating the lower roll to wind a mop thereon or unwind the same therefrom. 55
6. A combined mop holder and wringer having a head comprising upper and lower yoke-like members, said lower member having a tubular shank on its transverse portion, the transverse portion of said upper member being slidably mounted in a transverse slot in the shank, the prongs of said lower member being channel-shaped in cross section and the prongs of said upper member being slidably mounted therein, a collar slidably mounted on the shank, a pair of arms rigidly connecting the collar to said upper member, a mop-holding lower roll journaled on the prongs of said lower member, an upper roll 60 having trunnions extending through longitudinally extended slots in the prongs of said lower member and journaled on the prongs of said upper member, a coiled spring compressed between an abutment in the shank 65 and said upper member and operative to yieldingly hold the rolls in co-operating wringing relation, and means for rotating the lower roll to wind a mop thereon or unwind the same therefrom. 70
7. A combined mop holder and wringer having a head comprising upper and lower yoke-like members slidably mounted the one upon the other, a lower roll journaled on the prongs of said lower member and an upper roll journaled on said upper member, said two rolls being movable into co-operating wringing relation by pressing the transverse portion of said members toward each other, and a crank on the lower roll having a 75 slideable hand piece movable into a seat in said upper member to hold the crank from turning and lock said two members against sliding movement in respect to each other. 80
8. A combined mop holder and wringer 85 having a head comprising upper and lower yoke-like members slidably mounted the one upon the other, the transverse portions of the yoke-like members being closely positioned to afford a hand grip, a lower roll journaled on the prongs of said lower member and an upper roll journaled on said upper member, said two rolls being movable into co-operating wringing relation by pressing the transverse portion of said members toward each other, and means for rotating the lower roll. 90
